UNITED STATES PATENT OFFICE.

HIRAM W. McDONALD, OF BUCYRUS, OHIO.

IMPROVEMENT IN LAMP-BRACKETS.

Specification forming part of Letters Patent No. 123,498, dated February 6, 1872.

Specification describing a certain Improvement in Lamp-Brackets, invented by HIRAM W. McDONALD, residing at Bucyrus, in the county of Crawford and State of Ohio.

It is well known that a great many accidents endangering the lives of people result from overturning coal-oil lamps and their consequent explosion. My invention is intended to provide against accidents of this nature by suspending the lamps in brackets fastened to the wall or other fixed object instead of resting them upon tables; and to this end it consists in forming a bracket with a detachable spring throat-piece or collar for clasping the stem or pillar of an ordinary coal-oil lamp between the foot and the bowl.

Figure 1 is a side elevation of my improved bracket carrying a lamp. Fig. 2 is a perspective view, showing the spring-collar detached from its socket on the end of the bracket.

The same letters of reference are used in both figures in the designation of identical parts.

The device illustrated in the drawing consists of a long screw-bolt, A, which is to be screwed into a wall, projecting therefrom a sufficient distance to keep the lamp clear of the same, and a spring-collar, B, constructed with flanges for attachment to a slotted socket on the outer end of the bolt. This is the simplest form of the holder, for the screw-bolt of which a bracket of simple or ornamental form may be substituted; but the construction of the socket and spring-collar will always be substantially like that shown. The socket C on the outer end of the bolt or bracket A is adapted for the reception of the flanges b b on the spring-collar B, is open on top, but provided with a bottom for sustaining the flanges b b,

and is provided with a vertical slot, c, in its outer side, reaching from top to bottom. The spring-collar B is a circular strap of metal, having its ends, which nearly meet, folded back so as to form the flanges b b. Each flange has a projecting lug, b', which enters corresponding slots c' c' in the edge of the socket C, thus locking the collar to the socket so that they cannot be accidentally separated. The collars will be made of different sizes to fit different lamp-pillars; but the flanges b b of one size of collar will be equal in dimensions to those of all other sizes, so that one socket will fit every size collar.

To attach a lamp to a holder or bracket, the spring-collar is drawn out of its socket to be sprung over the stem of the lamp, which done, its flanges are again inserted in the socket, the neck of the collar passing down the slot in the latter.

What I claim as my invention, and desire to secure by Letters Patent, is—

1. A device for suspending ordinary coal-oil lamps from walls, composed of a bracket or bolt, A, slotted socket C c fixed thereto, and the detachable flanged spring-collar B b b, substantially as set forth.
2. The lugs b' b' on the spring-collar, in combination with corresponding slots c' c' of the socket, substantially as and for the purpose specified.

In testimony whereof I have signed my name hereto this 27th day of December, A. D. 1871, in the presence of two attesting witnesses.

HIRAM W. McDONALD.
